S. F. BROHMAN

RAILROAD TIE

Filed May 19, 1927

Patented Oct. 2, 1928.

1,685,980

UNITED STATES PATENT OFFICE.

SAMUEL FREDERICK BROHMAN, OF COCHIN, SASKATCHEWAN, CANADA.

RAILROAD TIE.

Application filed May 19, 1927, Serial No. 192,735, and in Canada May 11, 1927.

This invention relates to improvements in railroad ties, and the objects of the invention are to facilitate the running of trains in providing a durable, simply constructed 5 metal tie for railroads to which are secured suitable retaining plates.

A further object is to provide a device of this character in which the several parts are readily accessible to inspection and repair, 10 and adapted to satisfactorily perform the functions required of it.

With these and other objects in view, the invention consists in the novel construction, combination and arrangement of parts as 15 described in the present specification, and illustrated in the accompanying drawings, which form part of the same.

Referring now to the drawings, in which like characters of reference indicate corresponding parts in each figure.

Figure 1 is an elevation of my improved tie with rail sections secured thereon.

Figure 2 is a top plan view.

Figure 3 is a section on the line 3—3 of 25 Figure 2.

Figure 4 is a section on the line 4—4 of Figure 2.

Figure 5 is a side elevation of a modified form for securing the rail sections on the 30 tie.

Figure 6 is a section on the line 6—6 of Figure 5.

Figure 7 is a modified form of tie adapted for soft ground.

Referring more particularly to the drawings, A designates the improved tie as a whole comprising a hollow metal portion 8 with sides tapering slightly towards the top 10 on which is a separately formed top 10 plate 9 in which are formed transverse 40 grooves 33 to engage with the rail section 12 rigidly secured thereon as shown in Figure 2 by means of a plate 13 on one side and bolts 14 and 15 extending through the top 9 and through said plate and through the bottom 16, securing nuts 16^a being provided for the bolts. The plate 13 is adapted at its inner end to follow the contour of the rail as at 17 to engage with and clamp the base 18 and web 19 respectively, of the rail 12. On the opposite side of the rail to the plate 13 are plates 20 and 21 rounded and suitably curved at their inner ends to engage and clamp the base and web of the rail 12. 55 Bolts 22 and 23 extending through these plates and through the top 9 and bottom 16

of the tie are provided, with securing nuts 24 therefor.

The plates 20 and 21 are secured by stay-bolts and nuts, and can be, when the latter 60 are loosened, swung outwardly to permit ready insertion of the rail sections. All the inside plates are preferably constructed to operate in this manner.

In Figure 2, a single inside plate 26 is 65 shown, secured by a short bolt 27 to the tie and engaging the base of the rail. In Figure 5 a modified form of construction is shown, in which the retaining plate 13 is 70 similar as in Figs. 1 and 2, but having single 75 inside plates 28, as indicated at 26 in Fig. 2, and secured to the top of the tie by a screw-threaded bolt 29.

In Figure 7, a further modified form of tie is shown, adapted for certain kinds of 75 roadbed having integral therein, lugs or angular extensions 30 and 31 on each side of the base 32.

As many changes could be made in the above construction, and many apparently 80 widely different embodiments of my invention, within the scope of the claims, constructed without departing from the spirit or scope thereof, it is intended that all matter contained in the accompanying 85 specification and drawings be interpreted as illustrative, and not in a limiting sense.

By the use of this tie thousands of dollars can be saved yearly in the operation of any 90 railway as cost of replacement and labor can be very materially reduced.

What I claim as my invention is:

1. A railroad tie comprising a substantially hollow body portion, a cover plate for the body portion formed with a transverse 95 groove adjacent each end to engage with rails, clamping plates on each side of the rails, and securing bolts extending through said plates, the cover and the body portion.

2. The railroad tie according to claim 1 characterized by the fact that a single clamping plate formed with a curved inner edge conforming to the contour of the rail is provided on one side of one rail and a pair of retaining plates conforming at their inner 100 ends to the contour of the rail and curved are provided on the other rail and adapted on the bolts being loosened to be swung outwardly.

In witness whereof I have hereunto set my hand.

SAMUEL FREDERICK BROHMAN.
